(57) **CLAIM**

The ornamental design for an electronic device with graphical user interface, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a front view of an electronic device with graphical user interface showing a image in a sequence;

FIG. 2 is a rear view of the electronic device with graphical user interface;

FIG. 3 is a left side view of the electronic device with graphical user interface;

FIG. 4 is a right side view of the electronic device with graphical user interface;

FIG. 5 is a top view of the electronic device with graphical user interface;

FIG. 6 is a bottom view of the electronic device with graphical user interface; and,

FIG. 7 is a front view of the electronic device with graphical user interface showing a second image in a sequence.

The portions of the electronic device shown in broken line form no part of the claim.

The appearance of the animated images sequentially transitions between the images shown in FIGS. 1 and 7. The process or period in which one image transitions to another forms no part of the claimed design.
